UNITED STATES PATENT OFFICE.

SAKICHI TOYODA, OF NAGOYA, JAPAN.

TAKING-UP DEVICE FOR CIRCULAR LOOMS.

Application filed January 10, 1928. Serial No. 245,641.

This invention relates to a taking-up device for circular loom, wherein the completed tubular fabric is positively propelled toward the taking-up rollers by special means.

According to the invention, a plurality of propelling rollers are arranged above the beating part of the loom and are connected to each other to form a polygonal unit, each roller being provided at both ends with bevel gears meshing with those of the adjacent rollers, and a driving shaft is operatively connected to at least one of said propelling rollers so as to cause simultaneous rotation of all propelling rollers, whereby the tubular fabric engaging with said polygon of propelling rollers is positively propelled toward the taking-up rollers.

The accompanying drawings illustrate a constructional example of the invention by way of example, in which:

Figure 1 is a front view of the circular loom fitted with the device according to this invention,

Figure 2 is an enlarged detail view,

Figure 3 is an end view of one of the propelling rollers shown in Figure 2.

In the circular loom shown in Figure 1, 1 is the base or bed, on which is supported an upright shaft 2. On the upper part of said upright shaft 2 is provided a ball 3, on which is swingably mounted a slay sole 5 having a circular reed 4. Secured to the upright shaft 2 is an arm 6 carrying a lifting roller 7 which, engaging with the under side of the slay sole 5, imparts a gyratory movement to the latter during the rotation of the upright shaft 2. The tube of warps A is operated by suitable shedding mechanism for forming a shed successively, and the shuttle B is automatically moved through the shed formed in the warps along the circular reed 4, in such a manner that the shedding motion is always produced at the point where the shuttle B is at the moment.

The invention will now be described as applied to the above-mentioned type of circular loom, but it is to be understood that the invention may be applied to other various types of loom for weaving tubular fabrics.

Referring to Figures 2 and 3 as well as Figure 1, above the beating part of the loom are provided a plurality of propelling rollers 8 which are operatively connected to

each other to form a polygonal unit, each roller 8 being rotatably mounted upon the bearing bracket 9, and being provided on each end with a bevel gear 10 integral with or fixed to it. Each roller 8 is connected to two adjacent rollers by the engagement of said bevel gears 10 at the ends thereof, as shown in Figure 2. One or more of the propelling rollers 8 is operatively connected to the driving shaft 11 by the engagement of the bevel gear 10 on one end of the roller 8 with the bevel gear 12 fixed to the inner end of the driving shaft 11, thus it will be seen that by the rotation of the driving shaft 11 all the propelling rollers 8 will be simultaneously driven.

The driving shaft 11 is operatively connected to the slay sole 5, through suitable mechanism, in such a manner that the driving shaft 11 is rotated according to the movement of the slay sole 5. But, it is to be understood that the driving shaft 11 may be driven from any other part independently of the slay sole 5.

Arranged above and beneath of the polygon of the propelling rollers 8 are guide rings 13, which serve to cause the tight engagement of the tubular fabric with the said propelling rollers 8, so that the tubular fabric is moved step by step toward the taking-up rollers during the rotation of the propelling rollers 8.

While the gear drive is shown for securing simultaneous rotation of the propelling rollers 8, it may be if desired replaced by any frictional drive.

What I claim is:—

A taking-up device for a circular loom, wherein a plurality of propelling rollers are arranged above the beating part of the loom and are connected to each other to form a polygonal unit, each roller being provided at both ends with bevel gears meshing with those of the adjacent rollers, and a driving shaft is operatively connected to at least one of said propelling rollers so as to cause simultaneous rotation of all propelling rollers, whereby the tubular fabric engaging with said polygon of propelling rollers is positively propelled toward the taking-up rollers.

In testimony whereof I affix my signature.

SAKICHI TOYODA.
